UNITED STATES PATENT OFFICE.

WILLIAM ZEHNDER, OF PITTSBURGH, PENNSYLVANIA.

FLOOR-SCRUBBING MACHINE.

1,408,331.

Specification of Letters Patent. Patented Feb. 28, 1922.

Application filed January 9, 1917. Serial No. 141,443.

To all whom it may concern:

Be it known that I, WILLIAM ZEHNDER, a citizen of the United States, residing at Pittsburgh, in the county of Allegheny and State of Pennsylvania, have invented new and useful Improvements in Floor-Scrubbing Machines, of which the following is a specification.

This invention relates to floor scrubbing machines, the object in view being to produce a simple manually controlled scrubbing machine of the class referred to, whereby floor surfaces may be effectively scoured and scrubbed, the only thing required of the operator being to push or trundle the machine back and forth over the floor, there being means for delivering suds water in the desired quantity to the scrubbing members of the machine.

With the above and other objects in view, the invention consists in the novel construction, combination and arrangement of parts, as herein described, illustrated and claimed.

In the accompanying drawings:—

Figure 1 is a side elevation of a floor scrubbing machine embodying the present invention, the rear portion of the tank and handle being omitted.

Figure 2 is a side elevation of the remaining part of the handle and tank not shown in Figure 1.

Figure 3 is a view partly in elevation and partly in cross section looking toward the funnel end of the tank.

Figure 4 is a plan view of the main body of the machine showing a fragment of the handle.

Figure 5 is a sectional view of the traction wheel showing also one of the main brush driving gears.

Figure 6 is a front elevation partly in section of the distributing pipe, the shields and other parts intimately associated therewith.

Figure 7 is an edge view of one of the combined clamps and braces.

The scrubbing machine contemplated in this invention comprises, in the preferred embodiment thereof, an oblong open center frame designated generally at 1. This frame is connected by an adjustable pivot means 2 to a handle coupling 3 which is fastened by means of one or more bolts 4 or the equivalent thereof to a handle 5 of suitable length and preferably of wood, the remainder of the machine being constructed

mainly of metal. The handle 5 has fastened to the rear end thereof a clamp 6 in the form of a strap which is fastened fixedly to the handle by means of bolts 7 or their equivalent, the curved portion 8 of the clamp 6 passing around and tightly embracing and clamping in position a cross head or handle bar 9 enabling the operator to use both hands in the operation of the scrubbing machine. 65

Superimposed upon and supported manually by the handle 5 is a liquid tank or reservoir 10. The tank is adapted to contain suds water or the like for scouring purposes. This tank at the rear end thereof is 70 formed with an inwardly dished portion 11 resembling a four sided funnel, all sides of which slope to a central opening 12 leading directly into the tank and normally closed by means of a plug or stopper 13 which is inserted in the opening 12 after the tank 10 has been filled. Angle irons or clips 14 connect the tank rigidly to the handle 5 as shown in Figure 3.

At its discharge end the tank 10 is provided with a reduced neck or nipple 15 which passes through an opening 16 in a tank supporting bracket 17 which is secured by fasteners 18 to the adjacent extremity of the handle 5, the bracket 17 resting upon the coupling member 3 above referred to. 80

Connected with the nipple 15 is the body 19 of a regulating valve or stop cock 20 by means of which the flow of liquid from the 90 tank 10 to the scrubbing brushes may be regulated or entirely cut off. A nipple 21 extends from the valve casing 19 and over the last named nipple is fitted one extremity of a flexible pipe or hose 22. The opposite 85 end of the hose 22 fits over a nipple or tubular extension 23 projecting from a liquid distributing pipe 24 which is arranged in a substantially horizontal position over the scrubbing brushes to be hereinafter 95 described. Supported by the distributing pipe 24 is an inverted V-shaped shield preferably of sheet metal, the same comprising a rearwardly extending and downwardly sloping portion 25, and a forwardly 100 extending and downwardly sloping portion 26, both portions of the shield having their free ends reinforced as shown at 27 by bending the marginal edge of each portion 25 and 26 around a suitable length of wire 110 or rod. The pipe 24 is supported in position by means of two or more clamps 28

each composed of a metal strap bent to encircle the pipe 24 and having the end portions thereof bolted or fastened together as shown at 29 and extended downwardly 5 to form braces 30 which are connected by fasteners 31 to the forward end of the frame 1. As shown in Figure 6, the pipe 24 is formed in the bottom thereof with a large number of perforations 32 thereby causing 10 the liquid contained in the pipe to be distributed upon the floor surface at all points in the length of said pipe and the full width of the machine.

The frame 1 is provided with bearings for 15 a transversely extending axle 33 which is rotatably mounted in said bearings and which has fast thereon between the opposite side bars of the frame 1, a traction and brush-driving wheel embodying a hub 33', a rim 20 34 and a body or web 35. This traction wheel is fastened to the shaft 33 by set screws 36. At one end, the shaft 33 is reduced and squared as shown at 37 to fit the correspondingly shaped central opening of a brush 25 driving spur gear 38 held in place on the squared portion of the shaft 32 by a screw 39 or its equivalent. The peripheral face of the traction wheel is formed with a plurality of annular seats 40 in which are 30 placed resilient tires 41 preferably of rubber to obtain the necessary frictional grip on the floor surface for the purpose of actuating the brushes which are shown as mounted on a rotary shaft 42 parallel to the shaft 33 but arranged adjacent to the front end 35 of the frame 1.

Two brushes 43 are employed, the same being arranged at opposite sides of the frame 1 and both having a fixed relation to 40 the shaft 42 so as to rotate therewith. Each brush comprises a substantially cylindrical body 44 which is fastened to the shaft 42 by means of a key 45 shown in the form of a screw threaded into a bore formed partially in the body 44 of the brush and partially in the shaft 42. This locks the brush to the shaft and prevents relative movement in any direction between the brush and the shaft by which it is carried. 45

50 Fastened to the inner end of one or both brushes is a spur gear 46, the fastening means being indicated at 47 and shown as consisting of any desired number of screws. The gear 46 is driven by the respective gear 38. The gears 38 and 46 may either be duplicated at opposite sides of the frame 1 or one set of gears may be omitted, it only being requisite to use one set of gears 38 and 46. This feature will be left to the option 55 of the manufacturer.

The body 44 of each brush is formed with inwardly extending radial grooves 48 each

of which is adapted to receive the head portion of a brush section, the same comprising bristles 49 of any desired material, the inner 65 end portions of which are glued together and held between binding strips 50 which may be of paper, cardboard or any suitable material the same being also glued to the inner end portions of the bristles. After 70 a brush section is inserted in its respective groove, a wedge-shaped retaining strip 51 is inserted in the body 44 so as to bear against the head of the brush section, said strip 51 being fastened in place by means of a key 75 52 which is threaded into a bore formed partially in the wedge-shaped strip 51 and partly in the body 44. Thus the brush sections may be readily removed and replaced or renewed as they wear away. 80

The construction of the machine hereinabove described and illustrated in the accompanying drawings is such that each and every part of the machine may be easily removed with the aid of a screw driver and a small wrench. The brushes are subjected to the most rapid wear but in view of the construction described and shown they may be easily removed and replaced or renewed. 85

After placing water or suds water or any other desired liquid in the tank 10, the valve 20 is adjusted to give the desired flow of liquid to the distributing pipe 24 from which it falls upon the brushes and floor directly in front of the machine. The machine is then pushed backward and forward over the floor surface in the same manner as the ordinary rotary carpet sweeper and vacuum cleaner, the result being that the floor is thoroughly scrubbed and cleaned, 100 the splashing of the water upon the person operating the machine or upon the walls of the room being prevented by means of the front and rear portions of the shield hereinabove described. 105

I claim:—

In a floor scrubbing machine, a main frame, wheels journaled on the frame, brushes mounted on the frame for rotation, means for rotating said brushes, a liquid 110 tank supported above the frame, a distributing pipe arranged above and in parallelism with said brushes, a hose connecting the distributing pipe with said tank, metallic strips surrounding said distributing pipe 115 and depending therefrom, said strips being secured to one end of the frame and supporting the distributing pipe in proper relation to said brushes, and a substantially V-shaped shield supported by said distributing pipe over said brushes. 120

In testimony whereof I affix my signature.

WILLIAM ZEHNDER.
